[57] CLAIM

The ornamental design for a lever handle for faucets or the like, as shown and described.

DESCRIPTION

FIG. 1 is a side elevational view of a lever handle for faucets or the like showing my new design, the other sides being the same as the side shown;

FIG. 2 is an end elevational view thereof; and

FIG. 3 is an elevational view taken from the end opposite that shown in FIG. 2.

Fig. 1.

Fig. 2

Fig. 3
